By Attorney

UNITED STATES PATENT OFFICE.

CHARLES BRADLEY AND THOMAS E. KENNEDY, OF WATONGA, OKLAHOMA.

RAILWAY METAL-TIE APPLIANCE.

Application filed June 24, 1922. Serial No. 570,545.

To all whom it may concern:

Be it known that we, CHARLES BRADLEY and THOMAS E. KENNEDY, citizens of the United States, residing at Watonga, county 5 of Blaine, and State of Oklahoma, have invented certain new and useful Improvements in Railway Metal-Tie Appliances; and we do declare the following to be a full, clear, and exact description of the invention, such 10 as will enable others skilled in the art to which it appertains to make and use the same, reference being had to the accompanying drawings, and to the characters of reference marked thereon, which form a part 15 of this specification.

This invention relates to railway tie plates of the type disclosed and claimed in Patent 1,387,562 to Charles Bradley, issued August 16, 1921.

20 It is the object of this invention to produce a metal tie that can be substituted for the wooden ties now so extensively employed. As is well known, the wooden tie is liable to become soft, due to rot, and to permit the 25 spikes to slip out or move, and for this reason it is a prolific cause of disastrous accidents.

By the employment of ties constructed in accordance with our present invention, substantially all danger due to the movement of 30 the rails on the tie is overcome. The tie is made almost entirely of metal and therefore does not rot, and as we have provided it with sliding plates for holding the rails in place, there is no danger of the rails becoming 35 loose.

In order to more clearly describe our invention, we shall have reference to the accompanying drawing, in which—

Fig. 1 is a top plan view of our improved 40 tie, parts being broken away to better show the construction;

Fig. 2 is a side elevation of our tie with parts thereof shown in section, taken on line 2—2, Fig. 1;

45 Fig. 3 is a longitudinal vertical section of a portion of our tie, taken on line 3—3, Fig. 1;

Fig. 4 is a transverse section taken on line 4—4, Fig. 2; and

50 Fig. 5 is a bottom plan view of a portion of our tie with the slide plates, anchor plates and ends removed.

The same reference characters will be used to designate the same parts throughout the 55 several views.

In the various figures numeral 1 represents

the rails of an ordinary railway, and 2 the tie in its entirety. Our improved tie consists of a channel-shaped member of a metal such as soft steel. This member has a bottom 60 3 and sides 4. The ends of each side of the tie are provided with projecting flanges 5 (Figs. 1 and 5) which serve as guides for the reception of the ends 6, whose sides 7 are provided with channels which cooperates 65 with the flanges 5 to hold in place. The lower ends of sides 7 have notches 8 which cooperate with a corresponding projection on the projecting portion 9. Each end 6 also has an upper flange 10 which projects over 70 the sliding plate 11. Centrally of the tie we provide an anchor plate 12 having downwardly extending flanges 13 which project over and engage the sides 4. A transverse rib 14 is secured to the under side of the 75 anchor plate 12, and extends from the inside of one side to the inside of the other side. A bolt 15 serves to hold member 14 and plate 12 in place on the tie. On each side of member 14 we provide angles 16 which are riveted to the sides 4 and provide a slot for the reception of member 14. The edges of plate 12 are rabbeted as indicated by numerals 17 (Fig. 3). The outer upper edges of sides 4 are provided with outwardly projecting 80 flanges 18 (Fig. 4) which serve as means for engaging corresponding slots in the sliding adjusting plates 11 and 19. The upper edges of the sides of the tie near the ends thereof are provided with notches 20 (Fig. 1) 90 for the reception of the base 21 of the rail 1. Within the ties near the ends thereof are wooden cushion blocks 22 upon which the rails rest; these blocks are of such thickness that they extend slightly above the upper 95 edge of notches 20 so that the bottom of the rail will not touch the metal sides of the tie.

In order to obtain the proper level of the upper surface of the cushion block 22, we provide between the bottom thereof and the 100 bottom of the tie one or more shims 23. The slot 20 is wider than the rail base, so that the latter does not come in contact with the vertical sides thereof. In the left hand end of Figs. 1 and 2, and in Fig. 3, we have shown a 105 rail held in place at points intermediate its ends, and in the right hand end of Figs. 1 and 2 and in Fig. 4, we have shown how the joints between two rails are formed and how they are clamped to the tie.

The rails 1 are put in place on the tie with the base thereof resting on the cushion block 110

22. The anchor plate 12 being removed, the sliding clamping plate 19 is put in place and slid over towards the rail, the sides 24 thereof engaging the flanges 18 in the manner 5 shown in Fig. 4. The anchor plate is then replaced and serves as a rigid abutment for the clamping plate. The end cover plate 6 being removed, the sliding clamping plate 11 is slid into place and then the end plate 6 is 10 put in place to rigidly hold the same from outward movement. It will be noticed that plates 11 and 19 are each provided with a projecting flange 25 which projects over the flanged sides of the rail base. The ends 15 of flanges 25 engage the rail web and positively prevent sidewise movement of the rail.

In order to provide for adjustment due to slight variations in the sizes of the parts, 20 we provide filler strips 26 of various widths that can be placed between the outer edge of the adjustable clamping plate 11 and the end cover 6. On the ties where the joints come, we provide sliding plates 11^a and 19^a, 25 which are slightly modified for the purpose of accommodating the fish plates 27. In order to insulate the rail from the ties so that they may be used for signalling purposes, we provide suitable insulating means, 30 such as fibre sheets 28, between the rail and the metal parts of the tie, the cushion block being provided with transverse channels 29 for the reception of the lower ends of the insulating members. The cushion blocks 22, 35 being made of wood, are good insulators and they, together with members 28, serve to completely insulate the rail from the tie. The outer end of each block 22 has a transverse channel 30 which accommodates the 40 bolt 31 and permits adjustment of the block. The anchor plate is of such width that when it is removed plates 19 and 19^a may be moved inwardly a sufficient distance to release the rail. Anchor plate 12 and sliding clamping 45 plates 19 are so proportioned as to width that they serve to properly space the rails. The bottom of our ties is provided with projections 32 which engage the roadbed and prevent sliding of the tie.

50 From the above description it will appear that we have invented a standard metal tie that is provided with means for adjusting it to the rails, and which also permits the rails to be thoroughly insulated from the tie.

55 Having now described our invention, what we claim is —

1. A metal tie for railways, comprising a

channel-shaped body member having outwardly projecting flanges on the ends of each side, an end cover plate provided with 60 grooved sides for the reception of said flanges, the upper edges of each side being provided with outwardly projecting flanges, clamping plates slidably connected with said flanges, notches in the upper sides near 65 the ends of the tie, and an anchor plate rigidly secured to the central portion of said tie and cooperating with the sliding clamping plates to prevent movement of the latter.

2. A metal tie for railways, comprising 70 a channel-shaped member, an anchor plate removably connected to the tie substantially midway between the ends thereof, a notch in the upper edges of each side near the ends, 75 outwardly projecting flanges on said sides on each side of the notches, a sliding clamping plate on each side of the notches, said plates having means for engaging the flanges of a railway rail, and means on the end of the tie for preventing outward movement of 80 the outer clamping plates.

3. A metal tie for railways, comprising a channel-shaped member, an anchor plate removably connected to the tie substantially 85 midway between the ends thereof, a notch in the upper edges of each side near the ends, outwardly projecting flanges on said sides on each side of the notches, a sliding clamping plate on each side of the notches, said plates having means for engaging the flanges of a railway rail, means on the end of the tie for preventing outward movement of 90 the outer clamping plates, and cushion blocks in said tie near the ends thereof.

4. A metal tie for railways, comprising a channel-shaped member, an anchor plate removably connected to the tie substantially 95 midway between the ends thereof, a notch in the upper edges of each side near the ends, outwardly projecting flanges on said sides on each side of the notches, a sliding clamping plate on each side of the notches, said plates having means for engaging the flanges of a railway rail, outwardly projecting flanges on the end of each side, a cover having grooves cooperating with said last named flanges and provided with means for preventing the outward movement of the outer sliding plates, and cushion blocks within 100 said channel-shaped member.

In testimony whereof we affix our signatures.

CHARLES BRADLEY.
THOMAS E. KENNEDY.
